(57) **CLAIM**

The ornamental design for an instrument panel, as shown and described.

DESCRIPTION

FIG. 1 is a perspective view of an instrument panel.

FIG. 2 is a rear elevational view of the instrument panel of FIG. 1.

FIG. 3 is a front elevational view of the instrument panel of FIG. 1.

FIG. 4 is a right side elevational view of the instrument panel of FIG. 1.

FIG. 5 is a left side elevational view of instrument panel of FIG. 1.

FIG. 6 is a top plan view of the instrument panel of FIG. 1.

FIG. 7 is a bottom plan view of the instrument panel of FIG. 1; and,

FIG. 8 is a perspective view of the instrument panel of FIG. 1 shown in use in a cockpit environment.

Broken lines in FIG. 8 are shown to illustrate environment that form no part of the claimed design.

1 Claim, 8 Drawing Sheets
